[57] CLAIM

The ornamental design for a contact lens inserter, substantially as shown and described.

DESCRIPTION

FIG. 1 is a front isometric view of a contact lens inserter showing my new design.

FIG. 2 is a rear isometric view thereof.

FIG. 3 is a side elevational view of the device for inserting a contact lens in the eye, the opposite side elevational view being a mirror image thereof.

FIG. 4 is a front elevational view thereof.

FIG. 5 is a rear elevational view thereof.

The top and bottom plan views of FIG. 3 are each identical to FIG. 3.

FIG. 1.

FIG. 2.

FIG. 3.

FIG. 4.

FIG. 5.
